UNITED STATES PATENT OFFICE.

SIMON A. D. BERTRAND, OF DAWSON, YUKON TERRITORY, CANADA.

ROAD-GRADING MACHINE.

No. 903,162.

Specification of Letters Patent.

Patented Nov. 10, 1908.

Application filed March 26, 1908. Serial No. 423,352.

To all whom it may concern:

Be it known that I, SIMON A. D. BERTRAND, of Dawson, in the Yukon Territory of Canada, have invented certain new and useful Improvements in Road-Grading Machines, of which the following is a specification.

My invention relates to improvements in machines designed for the purpose of rounding up the surface of a highway removing the earth or gravel from the edge of the road and depositing it in the middle with the desired slope or angle on each side.

A further object is to provide a machine of simple compact construction, in which the cutters or shares used for scraping the gravel, are separately or collectively under the immediate control of the operator to permit the depth of the cut to be controlled and to allow the machine to clear any obstruction which might cause damage, or for the purpose of equalizing the quantity of gravel handled by either one or both of the grading shares.

25 A further object is to provide a grading machine capable of performing at one operation the work usually requiring two operations with the ordinary type of grading machine.

30 A further object is to provide means whereby the side or lateral thrust tending to force the machine laterally with respect to the desired direction of movement, is avoided.

35 A further object is to provide a road grading machine in which the force applied is utilized entirely for the purpose of cutting and moving the earth or gravel to the desired point, one cutting blade or share controlled 40 by the operator furnishing the desired resistance to the opposite cutter, thus equalizing the strain and avoiding waste of the power through side thrust.

The invention consists generally in various 45 constructions and combinations, all as hereinafter described and particularly pointed out in the claims.

In the accompanying drawings, forming part of this specification, Figure 1 is a plan view of a grading machine embodying my invention. Fig. 2 is a longitudinal sectional view of the same.

In the drawing, 2 and 3 represent crank axles, in alinement with one another, having 55 carrying wheels 4. These axles have suffi-

cient eccentricity to allow the grading shares or cutters to be cranked for the purpose of raising or lowering them. The grading shares consist of blades 5 and 6 having lower cutting edges 7 and connected with one another by cross bars 7', 8, 9 and 10. Upon these cross bars floors or platforms 11 are arranged. The grading shares converge from their forward toward their rear ends and the effect of such an angle is to direct 65 the gravel at the sides of the road toward the middle as the machine is drawn along.

A cross piece 12 is provided between the bars 8 and 9, and above the floors 11 and this cross piece has bearings 13 and 14 on 70 the crank axles. Levers 15 and 15^a are secured on the inner ends of the crank axles and have ratchet mechanisms 16 to engage the teeth of racks 17 that are secured to the floors 11 and the cross bars 8 and 9. By 75 the operation of these levers the grading shares can be raised or lowered, one side tilting up as the other tilts down to adapt them for the work to be performed. By the adjustment of these levers the operator 80 on the machine can swing one side of the grading frame to a position where its cutting share will dig into the soil and direct the material up toward the middle of the road. The other cutting share may, during this operation, be raised out of contact with the ground and be temporarily inoperative.

In front of the grading frame I provide a forward axle 18 having carrying wheels 19 and a draft connection 20. A draft connection 21 is pivotally attached at its rear end to the forward cross bar 7' and has a king bolt connection 22 at its forward end with the axle 18. A lever 23 pivoted on a quadrant 24 has a link connection 25 with a bar 26 on the draft connection 21, the operation of said lever tending to raise or depress the forward end of the grading frame and the cutting edges of the shares.

100 I claim as my invention:

1. A road-grading machine, comprising two cutters or shares, set at equal angles and distances from the center line, a divided axle having an eccentricity between its pivotal point and supporting wheels, a lever rigidly attached to each half of axle, suitable means for attaching said cutters or shares to said axle, substantially as set forth.

105 2. A road-grading machine comprising

110

two grading shares or cutters, crank axles and carrying wheels therefor, said shares converging toward one another from the front to the rear of the machine, and journaled on said crank axles, levers secured on said axles and whereby said shares may be raised or lowered, and a draft connection attached to the forward portion of said shares.

10 3. A grading machine comprising two crank axles and carrying wheels therefor, said axles being in alinement with one another, grading shares converging from the front toward the rear, and cross bars connecting them with one another, means supporting said shares on said axles and allowing them to be raised or lowered inde-

pendently of one another, and operating levers secured on said axles.

4. A road grading machine comprising 20 grading shares converging from front to rear and a connecting frame between them, means comprising crank axles and levers therefor for raising or lowering said shares, a draft connection attached to the forward 25 end of said frame and means for tilting the forward portion of said shares and frame.

In witness whereof, I have hereunto set my hand this 6th day of February 1908.

SIMON A. D. BERTRAND.
